LAWRENCE Y. SPEAR, OF QUINCY, MASSACHUSETTS, ASSIGNEE TO ELECTRIC BOAT COMPANY, OF NEW YORK, N. Y., A CORPORATION OF NEW JERSEY.

MEANS FOR EMPTYING SUBMERGENCE-TANKS IN SUBMERGIBLE BOATS.

964,943.

Specification of Letters Patent. Patented July 19, 1910.

Application filed November 18, 1907. Serial No. 402,749.

To all whom it may concern:

Be it known that I, LAWRENCE Y. SPEAR, a citizen of the United States, residing at Quincy, in the county of Norfolk and State 5 of Massachusetts, have invented certain new and useful Improvements in Means for Emptying Submergence-Tanks in Submergible Boats; and I do hereby declare the following to be a full, clear, and exact description of the invention, such as will enable others skilled in the art to which it 10 pertains to make and use the same.

The invention herein described comprises improved means for expelling water from 15 the submergence tanks of submarine or submergible boats by means of compressed air or the like.

In boats of this character as they have 20 been constructed up to the present time it has been customary to make the submergence tanks of different strengths, these several tanks being known as the high pressure and low pressure tanks, respectively. The 25 low pressure tanks are intended to be emptied only at shallow depths of submergence, and when a correspondingly low pressure is required for the expulsion of the water. The high pressure tanks are intended to be emptied at the greater depths of 30 submergence when the external pressure is higher and they are constructed to withstand the necessary internal pressure for this purpose. For the purpose of expelling the water from these several tanks, it has been 35 customary to store air in the vessel in a high pressure reservoir and to pipe it to the several tanks through reducing valves which reduce the pressure to different degrees; that is, for example, the low pressure submergence tanks have been connected to mains 40 in which the pressure has been reduced to ten pounds and the higher pressure submergence tanks have been connected to mains in which the pressure has been reduced to 45 fifty pounds and to one hundred pounds. With this arrangement, when it is desired to expel the water from any one of the submergence tanks an appropriate valve is 50 opened to put that tank into direct communication with the air supply main which is connected to it, and allow the air to blow the water out of the tank. This system involves a considerable waste of compressed air since the tendency is, in order to insure 55 the complete emptying of the tanks, to al-

low the air to flow even after the tanks are completely emptied. The system furthermore involves a complicated arrangement of service pipes since these pipes must be maintained at different pressures as above 60 described. Furthermore, it often occurs that a submergence tank is only partially filled with water and when the pipe connecting the tank with the external water is opened, preparatory to emptying the tank, 65 water from the outside will flow in before the air pressure in the tank has reached the necessary point to cause the expulsion of the water, thus wasting air and power, as well as disturbing momentarily the position of 70 the vessel.

The object of the present invention is to simplify this system and save the waste of air which is involved in it. The nature of the means adopted for this purpose will be 75 understood from a consideration of the following description and the accompanying drawing.

The drawing is a central longitudinal section of a submarine or submergible boat 80 equipped with the improved system.

Separate submergence tanks, as many as may be desired, are formed by inclosing portions of the interior hull of the vessel, as the portions *a*, *b* and *c*, by bulkheads. These 85 submergence tanks may be of the ordinary high and low pressure type. For example, it may be assumed that the tank *a* is adapted to withstand only ten pounds pressure, the tank *c* fifty pounds, and the tank *b* one hundred 90 pounds. Indeed the improved system may be applied directly to the now common type of submarine boat without any change in the submergence tanks. Each of these tanks is connected with the external water 95 by a suitable pipe controlled by a valve. Such pipes are shown at *a'*, *b'*, *c'*, controlled by the valves *d*, *e* and *f*.

Each submergence tank is provided with a pipe, as *g*, *h* and *i*, for admitting the compressed air thereto and each of these pipes is provided with a three-way valve *g'*, *h'* and *i'*, which valves are capable of putting the tanks into communication with the manifold *k* directly, or with the interior of 100 the boat. When the pipes are in communication with the manifold *k* they are ready to allow a passage of compressed air from the manifold to the respective tanks, and when they are in communication with the 105

110

interior of the boat they are prepared to allow an escape of the air from the tanks into the interior of the boat as the water enters the tanks. It will be understood that 5 the valves for allowing the escape of air from the tank as water enters may be mounted directly on the tanks instead of in the pipes leading thereto, or they may be so mounted as to discharge outside of the boat 10 if that is desirable.

The manifold k has three valves k' , k'' and k''' which control the passage of compressed air from the high pressure reservoir or reservoirs l through the pipes l' to the 15 respective pipes g , h and i leading to the submergence tanks.

Connected into the upper portion of each of the submergence tanks is a tell-tale pipe, as m , n and o , and to each of these tell-tale 20 pipes is connected a pressure gage, as m' , n' and o' , the gages being thus arranged to indicate the pressure within the submergence tanks. These gages are preferably mounted on a gage board in plain view of 25 the man operating the air system and on the same board is mounted a gage p' which is connected through the tell-tale pipe p to the water on the outside of the vessel, this gage thus serving to indicate the external 30 pressure at every depth of submersion. I prefer to so adjust this gage p' that it will indicate the pressure at the lowest part of the lowest tank.

The operation is as follows: For the purpose of submersion the valves d , e and f are opened allowing water to flow into the submergence tanks, the air in those tanks displaced by the water escaping through the valves g' , h' and i' , which are properly set 40 for that purpose. When the vessel is sufficiently submerged the valves d , e and f are closed. When it is desired to expel water from any or all of the submergence tanks, the valves g' , h' and i' having been set to 45 put the tanks into communication with the manifold, the appropriate valves in the manifold are opened, allowing the air from the high pressure reservoirs to enter the submergence tanks and this air is allowed to flow until the pressure registered by the gages m' , n' and o' exceeds the pressure indicated by the gage p' , that is, the external pressure. The valves d , e and f are then 50 opened and the water is expelled. By this arrangement it is possible to expel the water from any or all of the submergence tanks from a single high pressure system without danger of destroying the tanks. By causing the pressure within the tanks to exceed the 55 pressure before the sea valves are opened any possibility of a flowing in of water into the tanks is avoided. The operator soon learns to what degree the pressure in the tanks must be caused to exceed the pressure 60 registered by the gage p' in order to expel

the water therefrom entirely, and he is thus enabled to prevent waste of the compressed air.

It will be understood that the manifold may be connected directly to the high pressure tanks commonly used as indicated in the drawing, or there may be interposed between the high pressure tank and the reservoir a pressure reducing valve of any desired capacity. It will also be understood 70 that the invention is not dependent upon the location of the submergence tanks within the hull of the vessel, or upon any particular relative arrangement of said tanks, and, instead of the special construction and arrangement of tanks illustrated, any other desirable or convenient construction and arrangement may be adopted for use, either 80 interiorly or exteriorly of the hull.

What I claim is:—

1. In a submarine or submersible boat, a plurality of submergence tanks including tanks discharging under high pressure and tanks discharging under low pressure, a single fluid pressure system connected to the 90 several submergence tanks for expelling the water therefrom, and means for indicating the pressure in each tank, whereby danger of exploding the low pressure tanks is avoided; substantially as described. 95

2. In a submarine or submersible boat, a plurality of submergence tanks including tanks discharging under high pressure and tanks discharging under low pressure and having conduits by which communication 100 with the external water may be established, a reservoir for containing a fluid under pressure, valve-controlled conduits extending from the said reservoir to the several tanks for admitting the pressure fluid thereto to 105 expel the water therefrom, and means for indicating the pressure in each tank, whereby high and low pressure submergence tanks may be operated from a single pressure system; substantially as described. 110

3. In a submarine or submersible boat, a plurality of submergence tanks including tanks discharging under high pressure and tanks discharging under low pressure and having valve-controlled conduits by which communication with the external water may be established and shut off at will, a reservoir for containing a fluid under pressure, valve-controlled conduits extending from the said reservoir to the several tanks for admitting the pressure fluid thereto to expel the water therefrom, means for indicating the pressure in each tank, and means for indicating the pressure of the external water; 115 substantially as described. 120

4. In a submarine or submersible boat, a plurality of submergence tanks including tanks discharging under high pressure and tanks discharging under low pressure and having conduits by which communication 130

with the external water may be established, means for increasing the pressure within said tanks at will, means for indicating the pressure in each tank and means for indicating the pressure of the external water; substantially as described.

5. In a submarine or submersible boat, a plurality of submergence tanks having valve-controlled conduits by which communication with the external water may be established and shut off at will, a reservoir for containing a fluid under high pressure, conduits extending from the said reservoir to the several tanks for admitting the pressure fluid thereto to expel the water therefrom, a tell-tale pipe extending from each reservoir, pressure gages attached to said tell-tale pipes to indicate the pressure in each tank, a tell-tale pipe extending from the external water, and a pressure gage attached to said pipe; substantially as described.
- 10 15 20 25 30 35 40
6. In a submarine or submersible boat, a

plurality of submergence tanks having valve-controlled conduits by which communication with the external water may be established and shut off at will, a reservoir for containing a fluid under high pressure, a manifold in communication with said reservoir, service pipes extending from the manifold to the individual tanks and a valve in the manifold controlling each service pipe, a tell-tale pipe extending from each reservoir, pressure gages attached to the said tell-tale pipes to indicate the pressure in each tank, a tell-tale pipe extending from the external water and a pressure gage attached to the said pipe, the said gages being all arranged within the view of the man operating the manifold; substantially as described.

In testimony whereof I affix my signature, in presence of two witnesses.
